UNITED STATES PATENT OFFICE

JESSE E. ESHBAUGH, OF FLINT, MICHIGAN, ASSIGNOR TO A C SPARK PLUG COMPANY, OF FLINT, MICHIGAN, A COMPANY OF MICHIGAN

AMMETER

Application filed February 2, 1931. Serial No. 512,854.

This invention relates to improvements in ammeters and has particular reference to ammeters of the heavy duty type capable of carrying a large current.

5 The improvements in the ammeter consist in mounting a die cast frame inside the usual ammeter casing. The frame has a recessed or hollow base and hollow upstanding posts at the ends thereof. A pair of contacts pass through the rear of the casing and the base and secure the two together. A flat piece of metal, having its ends secured to the contacts and to the base and the intermediate part coiled, forms the conductor for the ammeter and a shunt connects the two contacts immediately at the points of attachment to the conductor. These parts are rigidly secured together and form a unit. The pointer swinging mechanism, 20 magnet, and dial are also interrelated in a second unit which is mounted on top of the posts of the frame. The unit comprises a frame or plate having a suitable portion thereof formed to receive the ends of a horseshoe magnet. A tongue bent from the plate and formed with a right-angularly bent end portion forms a means for mounting the shaft of the pointer. The magnet is placed in the recess in the plate and the dial then 25 placed over the magnet. A pair of screws pass through the dial and plate and into the posts to secure the unit to the base and in cooperative relation with the conductor.

30 Referring to the drawings:

35 Figure 1 is a front elevation of the ammeter with parts broken away to illustrate certain portions of the invention.

Figure 2 is an expanded view of the ammeter parts.

40 Figure 3 is a section on the line 3—3 of Figure 1.

Figure 4 is a plan view of a modified form of ammeter mechanism with the dial removed and shown in dotted outline.

45 Figure 5 is a side elevation of the structure of Figure 4.

Figure 6 is an expanded view of parts of the modification of Figures 4 and 5.

50 Referring to the drawings, the numeral 2 indicates the casing of the ammeter. The

casing has the bezel 4 secured as at 6 to flange 8 on the casing. The ring 10 is confined between the bezel and casing and supports the glass 12.

Mounted in the bottom of the casing 2 is the frame 14. The frame is secured to the casing by means of the contact bolts 16 which extend through openings in the casing and in the base 18 on the frame 14 and have the nuts 20 to rigidly hold the casing 2 between the insulating sheets 22. The bottom of the base 18 is recessed or hollow as shown in Figure 3, the purpose of which is to accommodate the nuts 20 and to decrease the amount of metal necessary in casting the frame. The contact bolts 16 have the contact heads 24 by means of which the shunt 26 and the ends 28 of the conductor 30 are secured to the base 18. Intermediate its ends 28, the conductor 30 is coiled as shown at 32 in Figures 2 and 6. The coil preferably has the recessed portion 34 to accommodate the axle of the pointer. A suitable piece of insulation 36 is positioned between the conductor ends 28 and the base 18. The ends of the frame 14 comprise the hollow uprights 38 and 40 each of which is provided with a threaded opening 42 and a recessed portion 44 at its upper end. Small projecting studs 45, one at each end of the base 18, fit into corresponding recesses in the casing bottom to position the frame relative to the casing. The parts so far described are rigidly secured together and form a unit.

55 The dial 70, magnet 82, pointer 46, and pointer swinging mechanism 48 are mounted on a frame or plate 50 and comprise a second unit. The plate 50 has the tongue 52 pressed therefrom, which tongue is provided with a right angularly bent end portion 54 and between the portion 54 and plate 50 the shaft 56 of the pointer swinging mechanism is mounted. A screw block 58 is threaded into the arm 54 and has a depression in one end thereof and a groove 60 in the other, the latter of which is to accommodate a screw-driver to adjust the screw. The block 58 is for the purpose of piloting in the depression thereof one end of the shaft 56. The opposite end of

the shaft 56 is piloted in an inwardly pressed portion 62 of the plate 50. The pointer 46 is rigidly mounted on the shaft 56 and has integrally formed therein the balance weight 64. An armature 66 is also secured to the shaft 56 immediately adjacent the pointer 46. A suitable opening 68 in the plate 50 accommodates the pointer 46 and allows it to extend over the dial 70 to swing thereover. The dial 70 has the openings 72 and the plate 50 has the openings 74 which mate with each other and with the openings 42 in the post 40. Suitable screws 76 extend to the openings 72 and 74 and are threaded into the openings 42 rigidly to hold the parts together, the plate 50 fitting in the recesses 44. The plate 50 is suitably shaped or pressed as shown at 78 in Figure 2 to accommodate the ends 80 of a horseshoe magnet 82, the magnet being held between the dial 70 and plate 50. The dial may be permanently secured to the plate 50 by screws screwed into openings 81 and 83. The plate 50 and the parts secured thereto comprise the second unit of the ammeter and this unit is removable from the first unit. The advantage of this construction is that if any of the parts of the more delicate pointer unit are damaged or broken this unit may be removed without disturbing the rest of the ammeter.

In the species of Figures 4, 5 and 6, a stamped frame 100 instead of the die cast frame 14 is used. The stamped frame is mounted in the usual outer casing and is generally of U-shape in cross-section and comprises the base 102, the web 104 and the upper wing portion 106. On the base portion, there is secured by means of the tongues 108 the insulating strip 110 on which the ends 112 of the conductor 114 are received. Suitable contact bolts 16 pass through openings 111 in the insulation and slots 113 in the base 102 and secure the ends 112 to the insulation 110 and to the base of the frame.

The central portion of the web 104 and wing 106 are open as shown at 116 to accommodate the pointer swinging mechanism or to provide an integral tongue 118 to form a mounting for the pointer shaft. Suitable recesses 120 are pressed in the upper wing 106 to accommodate the ends 80 of the magnet 82. The shaft 56 and pointer 46 are the same as in the species of Figure 1 and may be mounted in the same way or, if desired, the block 58 may be omitted as shown in Figure 5. When the magnet 82 has been placed in the recess 120, the dial 70 is placed thereover and secured thereto by means of the screws 76 passing through openings in the dial and threaded into openings 122 in ears 124 formed integral with the wing portion 106 of the frame.

As in the case of the species of Figure 1, the conductor 114 is formed with a coil 32 in-

termediate its ends. The conductor of the species of Figures 4 to 6 is formed of a straight strip of metal and has portions bent at right angles as shown at 126 to form the contact ends of the coil 32. The forming of the conductor from the flat strip of metal results in the saving of considerable material and is to be preferred. The conductor of Figure 6 may be used with the species of Figures 1 to 3.

The cross-sectional area of shunt 26 will not be the same for all installations for the amperages will vary and where the amperage is low, no shunt is required or needed. Where a shunt of a definite cross-sectional area will be proper for one installation of the ammeter, a second installation will have a different current or amperage and to accommodate the shunt to these different amperages, a different shunt 26 of the same shape but of a different thickness of metal is used. The purpose of this is to use the same dies in the operation of stamping the shunt.

I claim:

1. In an electrical measuring instrument, a casing, a frame secured in the casing and having a plurality of posts, contacts mounted in said frame, a conductor secured to said contacts and extending away from said frame, a plate secured to said posts, a magnet supported on said plate, a pointer and axle support formed on said plate, and a dial secured to said posts over said plate.

2. In an electrical measuring instrument, a casing, a frame unit including a frame having a plurality of posts, a plurality of contacts secured to the frame, and a conductor secured to the contacts and frame, a pointer unit including a supporting frame secured to the posts, a shaft support formed on said supporting frame, a pointer secured to the shaft, a magnet supported on the supporting frame and a dial secured to the posts over the supporting frame.

3. In an electrical measuring instrument, a casing, a frame unit including a frame having a plurality of posts and resting on its base against the casing back, a pair of contacts passing through the casing and base and rigidly secured thereto, a shunt connecting said contacts, a conductor coil secured to said contacts, and means mounted on said posts to indicate the current passing through the conductor.

4. In an electrical measuring instrument, a casing, a pointer unit comprising a plate, a pointer shaft, a tongue bent from the said plate to form a support for the shaft, a pointer rigid with the shaft, and a magnet mounted on the plate to bias the pointer, a frame in the casing, a plurality of uprights on said frame for supporting said unit, and a conductor secured to said frame.

JESSE E. ESHBAUGH.
